CONTAINER HOLDER

Herbert L. Parsons, New Brunswick, N. J.

Application January 3, 1952, Serial No. 264,710

2 Claims. (Cl. 248—154)

1

This invention relates to container holding apparatus and is directed particularly to improvements in apparatus of this type for holding ice cream containers in fixed position in a refrigerating compartment.

Ice cream is usually packaged in two and one-half gallon containers at the time of manufacture and the filled containers distributed to retailers where they are stacked in horizontal rectangular refrigerators in rows of two each, two high in each refrigerator compartment. Ice cream is dispensed from the top container of each stack by scoops, dips or the like as required.

In dispensing the ice cream, it is the usual practice to dip with the right hand while holding a cone or receptacle in the left hand, and unless the ice cream container is held firmly in some manner when the ice cream is being dipped it will rotate or wobble. This makes it very difficult for the clerk to dip the ice cream and results in considerable inconvenience, irritation and inefficiency. Furthermore, the sidewalls of the refrigerator are, as a rule, covered with frost and ice from a position at the bottom of the rubber frost ring to the bottom of the refrigerator. When the container rotates or wobbles against the sidewall, the ice or frost is frequently knocked into the ice cream container which is obviously quite detrimental to the product. It is apparent, therefore, that suitable means must, or desirably should, be provided to hold the container firmly at all times.

Also, the depth of the usual refrigerator compartment is excessive for the height of the two containers and as a consequence the top of the top container of a stack is normally positioned somewhat below the rubber frost ring. This requires the clerk to extend his arm into the refrigerator further than is necessary, which results in discomfort and possible injury to the clerk caused by rubbing his arm or elbow against the frosted or iced sidewall of the refrigerator, particularly when the ice cream is low in the container. It also requires, in the case of newly delivered containers in which the ice cream is frequently too hard or unworkable, that the top of the refrigerator be left open or completely off so that the ice cream may soften prior to dipping or dispensing. The refrigerator losses incurred by this practice result in excessive use of the compressor and motor and reduced service life. Furthermore, when loading the refrigerator, the excessive depth thereof frequently results in the attendant dropping the container to the refrigerator bottom, thereby causing an impact which is quite detrimental.

2

A primary object of the present invention is the provision of a simple and relatively inexpensive apparatus which will firmly and positively hold ice cream containers in fixed position in a refrigerator compartment so that they cannot rotate, shift, wobble or otherwise move when ice cream is being dipped therefrom.

A further object of the invention is the provision of a container holding apparatus which will positively grip the top of a container with a substantially constant unyielding pressure to hold it in fixed non-rotative position and which will simultaneously support the sides of the container, and also of a second container on which the first container may rest, so that the walls of the containers will not be crushed or bulged out.

A still further object of the invention is the provision of a container holding apparatus of rigid construction which forms a partial enclosure for a container or containers and which is provided with open spaces on opposite sides of a container or containers, through which the hands of a clerk may pass in inserting or removing the containers.

Still another object of the invention is the provision of a container holding apparatus which will act as a braking device when a container is inserted therewith in a slightly tilted position thereby avoiding the detrimental and frequently damaging impact on the bottom of the refrigerator caused by dropping the container.

A further object of the invention is the provision of a container holding apparatus which will hold a container in fixed elevated position in a refrigerator compartment whereby the ice cream adjacent the top portion of the container will become slightly softer for ease in dispensing and whereby the ice cream may be dispensed with greater facility and ease and without dislodging and knocking ice or frost from the sidewalls of the refrigerator into the open ice cream container.

These and other objects and advantages of the invention will become more apparent by reference to the accompanying drawings illustrating preferred embodiments of the invention.

In such drawing:

Fig. 1 is a side elevational view of one form of container holding device according to the invention, positioned in a refrigerator compartment, the latter being shown in broken lines;

Fig. 2 is a top plan view of the container holding device of Fig. 1;

Fig. 3 is an end view thereof;

Fig. 4 is an enlarged sectional view of a por-

tion of the device showing the mounting of the toggle clamp assembly;

Fig. 5 is an end view of the portion of the device shown in Fig. 4;

Fig. 6 is a top view of the toggle clamp assembly;

Fig. 7 is a perspective view of the clamping member;

Fig. 8 is an end view similar to Fig. 3 of a modified form of the invention.

In the drawings the numeral 10 designates a freezing compartment of a refrigerator 11, having the usual insulated walls 12 and rubber frost ring 13. The refrigerator 11 may be of suitable type in general use for the storage of ice cream and similar containers and will usually include a plurality of adjacent compartments separated by intervening partitions. Ice cream containers, designated herein by the numeral 14 are arranged in the freezing compartment in stacks of two, the lower container 14 of each stack usually, but not always, being an inverted empty container. At the present time such containers are made of cardboard or similar material and are readily susceptible to crushing, bulging or other deforming forces.

In one preferred form the device of the invention consists of a supporting base structure 15 on which the containers rest and clamping and supporting elements 16 rigidly secured to the base structure 15 and extending upwardly therefrom on opposite sides of a stack of containers. The elements 16 form a partial enclosure for a stack of containers and serve to positively clamp the containers to the base structure and simultaneously support the sidewalls thereof against bulging or crushing.

The base structure 15 consists of a base member 17 and supports 18. The base member 17 preferably, though not necessarily, consists of a flat steel plate approximately $\frac{1}{8}$ of an inch in thickness and of such shape and size as to be readily insertable into and removable from the freezing compartment. While the base member 17, as shown, is designed to support two adjacent stacks of containers in the usual refrigerator compartment it will be appreciated that the size may be varied to accommodate one or any desired number of stacks.

The base plate 17 is supported in spaced relation to the bottom of the refrigerating compartment by the supports 18, desirably formed of wood, and secured to the base plate in any suitable manner such as by screws or the like. Three such supports may desirably be used, spaced as shown, and with the spaces between the supports preferably left open to permit access thereto and free circulation of air under and around the base member.

The base plate 17 is supported at a height above the bottom of the refrigerator compartment such that the top portion of the top container 14 is positioned in the warmer area of the refrigerator slightly above the bottom edge of the rubber frost ring 13. This facilitates dispensing by bringing the container within easy reach of a clerk and further by permitting the ice cream at the top of a newly inserted container to soften. It also eliminates the possibility of ice or frost being knocked from the sidewalls of the refrigerator compartment into the container when the ice cream is being dispensed as well as the discomfort and possible injury to the clerk occasioned thereby.

The clamping and supporting elements 16 con-

sist of uprights 19, toggle clamps 24 and guides 40. The uprights 19 are arranged in pairs to accommodate each stack of containers, the uprights of each pair being mounted in diagonally opposite corners of the stack receiving half sections of the base in spaced apart relation so as to be disposed on opposite sides of a stack of containers positioned therebetween. Uprights 19 are preferably formed of rigid steel rods or bars screw threaded at their lower ends as at 20 for threaded engagement with threaded bushings 21 welded or otherwise secured to the underside of the base plate 17. Uprights 19 project above the base plate 17 a distance substantially equal to the height of two stacked containers 14 and by virtue of their threaded engagement with the bushings 21 may be adjusted for small variations in height of such containers.

Adjacent the top portions thereof the uprights 19 are provided with toggle type clamps 24 adapted to be positively moved into unyielding pressure engagements with the opposite top edge portions of the top one of a stack of containers to hold them against rotation and lateral shifting movement while ice cream is being dispensed. In a preferred construction the clamps 24 each consist of a toggle lever 25, a clamping member 26 and a locking arm 27.

The toggle levers 25 are pivotally mounted as at 28 in slotted end portions 29 of the uprights 19 and have transversely flattened, curved end portions 30 provided with elongated apertures 31 and retained therein in any suitable manner as by washers 32 and pins 32a secured to the locking arms. Handles 33 are provided at the upper ends of the locking arms for the convenience of a clerk in swinging the toggle levers 25 to and from their locking positions.

The clamping members 26 are pivotally connected, as at 34, to intermediate portions of the toggle levers 25 and are preferably curved inwardly around the pivotal connections 28 in order to secure the desired toggle action. Clamping plates 35 are secured to the upper ends of the clamping members 26 in any suitable manner, as by welding, and may desirably comprise substantially horizontally disposed mounting portions 36 and downwardly extending locking portions 37 desirably connected to the mounting portions 36 by intermediate curved portions 38.

In the operation of the clamps 24 the clerk grasps the handle 33 of the locking arm 27 and pulls upwardly thereon to swing the toggle lever 25 in a counter clockwise direction as viewed in Fig. 4. This raises the clamping member 26 so that the locking portion 37 thereof may be swung inwardly over the top edge portion of the top container of a stack. The clerk then pushes down on the locking arm to swing the toggle lever 25 in a clockwise direction thus bringing the clamping plate 35 into positive unyielding pressure engagement with the top edge portion of a container, such clockwise swinging movement being continued until the clamp is in locked position.

The pressure exerted by the clamps 24 may be varied as desired by adjusting the uprights 19 up or down in the manner hereinbefore described. Such pressure, however, should be a positive unyielding pressure of sufficient magnitude to securely grip the containers in order to prevent rotation or other movement thereof while ice cream is being dispensed.

The guides 40 are carried by the uprights 19 and form therewith a substantially rigid struc-

ture which partially but not completely encloses the stacked containers 14. Guides 40 are formed of flat metal strips or plates, preferably of steel and consist of horizontal bracket members 41 mounted on the uprights 19 and vertical guide members 42 carried by the brackets 41. The brackets 41 extend laterally and inwardly from the uprights 19 and are preferably curved on the arc of a circle having a radius approximately $\frac{1}{8}$ of an inch greater than the radius of a container.

The brackets 41 of opposed uprights 19 are designed to partially enclose a container 14 so as to leave between opposed ends thereof a space of sufficient extent to permit the hand of a clerk to pass therebetween to facilitate insertion or removal of a container. Aside from this the length of such brackets may be varied to enclose more or less of the circumference of a container.

The guide members 42 are secured to the inner faces of the brackets 41 in laterally spaced relation thereon for snug engagement with the opposite side wall portions of a container positioned between a pair of uprights 19. Such guide members engage and effectively support the walls of the containers, particularly a lower empty container, against crushing and bulging due to the weight of the upper filled container and also due to the pressure of the clamps 24. Such guide members further serve to guide inserted containers into correctly stacked alignment one above the other. Also by slightly tilting a container when it is being inserted the guide members 42 may be made to act as brakes thereby making it easier for an attendant to insert a container without dropping it with consequent possible damage to the bottom of the refrigerator.

The embodiment of the invention thus far described is designed to be removably mounted in an existing refrigerator compartment. In the modified embodiment shown in Fig. 8 the device is constructed as an integral part of the refrigerator. For this purpose the uprights 19 are permanently secured to the bottom 43 of a refrigerator compartment in any suitable manner such as by welding or the like and a container supporting base plate 44 slidably mounted on the uprights 19 and vertically adjustable thereon to accommodate small variations in height of the containers by a plurality of screw lifts 45. The screw lifts 45 may be rotatably mounted in a member 46 secured to the bottom 43 of the refrigerator compartment and screw threadedly engage a threaded boss 47 of the base plate 44. Squared portions 48 are provided at the top of the screw lifts 45 for cooperation with any suitable mechanism or tool for individual or simultaneous rotation of the screw lifts to raise or lower the base plate 44.

In the operation of the device a first container which may be a full container or an inverted empty container is inserted between the guides 40 from the top and lowered to the base member 17 (Figs. 1-7) or 44 (Fig. 8). In the event a full container is used it may desirably be tilted when introduced so as to obtain the advantage of the braking action afforded thereby the guide member 42. A second container is then inserted in a similar manner on top of the first container. The guide members 42 guide the containers into correctly aligned and stacked relation and simultaneously brake the fall thereof. When the containers are thus stacked the clamps 24 are placed in clamping position as previously described to 75

secure the containers in fixed position for dispensing ice cream.

It will thus be seen that the present invention provides an improved device for holding containers such as ice cream containers in non-rotatable, non-shiftable position for dispensing ice cream. The particular arrangement of uprights, guides and clamps, secured to a base, provides a substantially rigid structure which partially encloses and supports the side walls of a container to prevent crushing or bulging thereof and which grips the containers with a positive unyielding pressure to hold them against rotation, lateral shifting or other movement while ice cream is being dispensed therefrom.

While I have illustrated and described preferred embodiments of the invention various modifications thereof will most likely occur to those skilled in the art to which the invention relates and may be made without departing from the spirit of the invention, the scope of which is indicated in the attached claims.

I claim:

1. A container holder comprising a base member, a pair of spaced substantially vertically disposed uprights extending upwardly from said base member, a plurality of transversely disposed substantially arcuate shaped brackets mounted on each of said uprights and extending laterally and inwardly therefrom to receive and partially enclose a container positioned therebetween, the opposing ends of said brackets being spaced a substantial distance from each other, a plurality of substantially vertically extending laterally spaced guide members secured to said brackets adapted to bear against a container for engaging opposite sides of a container positioned therebetween to support the container against lateral shifting movement, and clamping means pivoted on toggle levers pivotally mounted on said uprights and engageable with the top edge portions of a container for securing the container in fixed position.

2. A container holder comprising a supporting base adapted to be positioned in a refrigerator compartment in spaced relation to the bottom thereof, a pair of uprights threadedly mounted in said base and extending upwardly therefrom in spaced apart relation, a plurality of arcuate bracket arms mounted in vertically spaced relation on each of said uprights and extending laterally and inwardly therefrom, the opposing ends of said bracket arms being spaced a substantial distance from each other, a plurality of laterally spaced vertical guide members secured to said bracket arms adapted to bear against a container for engaging opposite wall portions of a container positioned therebetween to support the container against lateral shifting movement, and toggle type clamping means pivoted on toggle levers pivotally mounted on said uprights adjacent the upper ends thereof and adapted to engage the top edge portions of a container with a positive unyielding pressure.

HERBERT L. PARSONS.
